ASSIGNORS, BY DIRECT AND MESNE ASSIGNMENTS, TO BARTON E. DEMING, OF
CLEVELAND, OHIO.

IRONING MACHINE.

Application filed May 9, 1921. Serial No. 468,069.

To all whom it may concern:

Be it known that we, WILLIAM G. YATES and GEORGE C. FATSCHER, citizens of the United States, and of the Republic of Germany, respectively, residents, respectively, of Cleveland, in the county of Cuyahoga and State of Ohio, and Lakewood, in the county of Cuyahoga and State of Ohio, have invented a certain new and useful Improvement 5 in Ironing Machines, of which the following is a full, clear, and exact description.

The object of this invention is to produce an ironing machine of low cost and high 15 efficiency; and particularly a machine with which ruffles and tubular garments, such as skirts, may be ironed by the same means which are employed in ironing flat work.

The invention consists in the construction 20 and combination of parts shown in the drawings and hereinafter described and pointed out definitely in the appended claims.

In the drawings, Fig. 1 is an end view of 25 an ironing machine which embodies the present invention; Fig. 2 is a front elevation thereof; Fig. 3 is a transverse sectional side view through the ironing shoe and pressure drum, and Fig. 4 is a detached view of the driving shaft and the part of the change 30 speed mechanism mounted thereon.

A built up frame 10 supports a fixed hollow ironing shoe 12, the front operative face of which is curved in the usual way to substantially fit a portion of the periphery of the rotatable ironing drum 20. Within 35 the shoe are means to heat its operative face, as for example, a long gas burner 13.

The ironing drum 20 has at its ends trunnions 21, 22; and these are rotatably mounted 40 in arms 23, 24, which are parts of a rocking frame, the other part of said frame being a rock shaft which is rotatably supported in bearings in the end members of the frame. These arms extend from the 45 rock shaft forward and preferably at a slight angle upward so that the weight of the drum will tend to rock the frame to carry the drum away from the shoe.

The arm 23 at the left end of the drum 50 (the opposite end to that at which the driving mechanism is placed) is so constructed that it may move out of supporting engagement with the drum, and may also be moved away from the end of the drum so that a 55 tubular garment, such as a skirt, may be

slipped over the drum,—after which the arm may be returned to its drum supporting position with relation to the drum.

In the construction shown for attaining this result the arm 23 is formed with a 60 U-shaped transverse notch 23^a near its end which furnishes the bearing for the adjacent trunnion 21. This arm 23 is bifurcated at its outer end and straddles the rock shaft to which it is pivoted on a pivot pin 26 65 which extends diametrically through the shaft.

The members of the frame are tied together near their front lower portion by the tie rod 40 to which a nonrotatable ratchet 70 wheel 41 is fixed. Adjacent this ratchet wheel a treadle lever 42 is mounted to rock on this tie rod, said treadle lever comprising the treadle arm 42^a and an upwardly extended arm 42^b. To this latter arm a pawl 43 75 is pivoted in position to engage the nonrotatable ratchet wheel 41. The arm 42^b of this treadle mechanism is connected with an arm 27 fixed to the rock shaft 25 by a link 44 which is composed in part of a coil spring 80 44^a. By stepping on the treadle arm 42^b the treadle lever is rocked and thereby the rock shaft 25 is rocked to carry the drum 20 toward the shoe. This movement puts the spring 44^a under tension so that the drum 85 is pressed yieldingly against the shoe. When by the rocking of the treadle mechanism this spring 44^a has been put under the desired tension, the pawl 43 will engage a tooth in the ratchet and thereby the parts will be 90 held in this adjusted position. The parts will be in this position when the ironing operation is going on. The operator will take the cloth to be ironed from the adjacent table 50 and push it rearward and cause it 95 to pass between the rotating ironing drum and the fixed shoe.

Near the front of the machine is a rocking pawl-release frame comprising two arms 51 which are loosely hung on the tie rod 40 and are connected by a long foot bar 52. A link 53 fixed to this bar 52 is connected with the tail end of the pawl 43. By stepping on this bar 52 the pawl will be rocked so that it 100 will release its engagement with the ratchet 41 whereupon the treadle mechanism will be free to rock and allow the drum to move 105 away from the shoe.

At the right end of the drum is the driving mechanism therefor. This includes of 110

necessity a gear fixed to the drum trunnion and a driving gear 32 mounted in axial alignment with the rock shaft 25, said gear being movable in the direction of its axis 5 into and out of engagement with gear 28. In the preferred construction, however, there are two gears 28, 29, of different diameters, fixed to the drum trunnion, and there are two driving gears 32, 33, of different diameters adapted respectively to engage the two gears 28, 29. The two gears 32, 33, are fixed to a sliding sleeve 31 which is mounted upon a shaft 37 which is mounted in axial alignment with the rock shaft 25. This sleeve is 10 provided with a circumferential groove 34 for engagement by a lever, which is not shown, whereby the sleeve may be moved lengthwise of the driving shaft to cause gear 32 to mesh with gear 28, or gear 33 to mesh with gear 29, whereby the drum may be driven at either of two speeds. The distance between gears 32, 33, is such that sleeve 31 may be moved to a neutral position, in which neither of the gears 32, 33, 15 may engage the associated gears 28, 29. By moving the sleeve from this neutral position in one direction to another the desired intermeshing of the gears 32, 33, with the corresponding gears 28 or 29 will be produced.

A drum support 56 is mounted on the bed or table 11 of the machine frame in a position such that it may be utilized to temporarily support that end of the drum 20 which is supported by the pivoted arm 23. It is preferably pivoted to the table so that when not in use it may be swung down out of the way when it is desired to introduce a tubular garment around the drum so that 25 it may be ironed, this device is turned up to operative position and then the drum is allowed to swing down into engagement therewith. The rocking frame will then be still further rocked until the U-shaped notch 23^a 30 is withdrawn from the trunnion 21. When this has been done the arm 23 may be swung on its pivot 26 into a position such as to completely uncover the end of the drum, and permit the tubular garment, such as a skirt, 35 to be passed over the end of the drum. When this has been done the arm 23 will be swung into operative position, and the rocking frame will be rocked and the drum will be picked up by said rocking frame in 40 readiness to serve the purpose for which it is provided.

Of course, this support for temporarily upholding the drum while its end is no longer supported by arm 23, may be omitted, 45 because the operator can with one hand swing the arm 23 out of engagement with the drum trunnion, and may at the same time with the other hand hold up the drum so as to permit the tubular garment to be 50 passed over it.

It will be noted that the end of the drum with which arm 23 engages is, even when said arm is engaging the trunnion, practically free and open so that a ruffle may be introduced between the end of the drum 55 and shoe and iron between them.

Having described our invention, we claim:—

1. In an ironing machine, the combination of an ironing shoe, a rotatable ironing drum, 75 a rocking frame having arms between which the drum lies and in which it is rotatably mounted, one of said arms being movable out of supporting engagement with the drum.

2. In an ironing machine, the combination of an ironing shoe, a rotatable ironing drum, a rocking frame having arms between which the drum lies and in which it is rotatably mounted, one of said arms being pivotally supported so as to be movable out of supporting engagement with the drum.

3. In an ironing machine, the combination of an ironing shoe, a rotatable ironing drum having end trunnions, a rocking frame comprising a rock shaft and two arms secured thereto in which trunnions on the drum are rotatably mounted, one of said arms having a U-shaped slot near its end to furnish the bearing for the adjacent drum trunnion, 90 which arm is pivotally connected with the rock shaft, means to actuate said rocking frame to carry the drum toward said shoe.

4. In an ironing machine, the combination of an ironing shoe, a rotatable ironing drum having end trunnions, a rocking frame comprising a rock shaft and two arms secured thereto in which trunnions on the drum are rotatably mounted, one of said arms having a U-shaped slot near its end to furnish the bearing for the adjacent drum trunnion, 100 which arm is pivotally connected with the rock shaft on a diametrically disposed pivot, means to actuate said rocking frame to carry the drum toward said shoe,—said means including a spring by which the drum will be yieldingly pressed against the shoe.

5. In an ironing machine, the combination of an ironing shoe, a rotatable ironing drum having end trunnions, a rocking frame composed of a rock shaft and two arms secured thereto in which trunnions on the drum are rotatably mounted, means to actuate said rocking frame, a driving gear in axial alignment with said rock shaft, a gear fixed to the adjacent drum trunnions, and means to move the driving gear into and out of mesh with the other gear.

6. In an ironing machine, the combination of an ironing shoe, a rotatable ironing drum having end trunnions, a rocking frame composed of a rock shaft and two arms secured thereto in which the trunnions on the drum are rotatably mounted, means to control the movements of said 125

- rocking frame, a driving shaft in axial alignment with said rock shaft, two gears differing in size fixed to the adjacent drum trunnion, a sliding gear sleeve having a splined connection with the driving shaft and carrying two gears differing in size and adapted to respectively mesh with the two gears on the drum trunnion, the distance between the two gears on the sliding sleeve being such that the two gears on the drum trunnion may both be disengaged from the gears on the sliding sleeve. 5
7. In an ironing machine, the combination of an ironing shoe, a rotatable ironing drum having end trunnions, a rocking frame comprising a rock shaft and two arms secured thereto in which trunnions on the drum are rotatably mounted, treadle mechanism, an arm fixed to the rock shaft and a link comprised in part of a coil spring connecting said arm and treadle mechanism. 10
8. In an ironing machine, the combination of an ironing shoe, a rotatable ironing drum having end trunnions, a rocking frame comprising a rock shaft and two arms secured thereto in which trunnions on the drum are rotatably mounted, treadle mechanism, an arm fixed to the rock shaft and a link comprised in part of a coil spring connecting said arm and treadle mechanism, and latch mechanism for latching said treadle mechanism in any of various positions. 15
9. In an ironing machine, the combination of an ironing shoe, a rotatable ironing drum having end trunnions, a rocking frame comprising a rock shaft and two arms secured thereto in which trunnions on the drum are rotatably mounted, treadle mechanism, an arm fixed to the rock shaft and a link comprised in part of a coil spring connecting said arm and treadle mechanism, and latch mechanism for latching said treadle mechanism in any of various positions, and means to release said latch mechanism. 20
10. In an ironing machine, an ironing shoe, a rotatable ironing drum, said shoe and drum being relatively movable so that one may be caused to move toward and from the other, a supporting stand beneath the drum, and separate supports for the ends of the drum at opposite ends of the stand in which the drum is rotatably supported, one of said supports and the corresponding end of the drum being relatively movable so as to permit the drum to be demounted at such end for the purpose of passing a substantially tubular garment in an endwise direction over the drum. 25
11. In an ironing machine, an ironing shoe, a rotatable ironing drum, said shoe and drum being relatively movable so that one may be caused to move toward and from the other, a supporting stand beneath the drum, and separate supports for the ends of the drum at opposite ends of the stand in which the drum is rotatably supported, one of said supports being movable out of supporting engagement with the drum. 30
12. In an ironing machine, an ironing shoe, a rotatable ironing drum, said shoe and drum being relatively movable so that one may be caused to move toward and from the other, supports at the ends of the drum in which the drum is rotatably supported, one of said supports being pivotally mounted so that it may be swung out of supporting engagement with the drum. 35
13. In an ironing machine, a supporting structure, an ironing shoe, a rotatable ironing drum, said shoe and drum being relatively movable so that one may be caused to move toward and from the other, spaced supports on the supporting structure in which the ends of the drum are rotatably supported, one of said supports having a substantially U-shaped drum supporting portion and being mounted to be movable toward and from the adjacent end of the drum which permits that end of the drum to be readily demounted, whereby a substantially tubular garment may be moved over the drum from one end thereof and caused to surround the same. 40
14. In an ironing machine, an ironing shoe, a rotatable ironing drum, said parts being relatively movable whereby one may be caused to recede from or approach the other, a pair of arms in which the ends of the drum are rotatably mounted, gearing at one end of the drum for rotating the same, the opposite end of the drum and its bearing being relatively movable, whereby said end of the drum may be readily demounted to permit a substantially tubular garment to be slipped over the drum from said end so as to surround the same. 45
15. In an ironing machine, an ironing shoe, a rotatable ironing drum, said parts being relatively movable so that one may be caused to move toward and from the other, trunnions on the end of the drum, a pair of arms in which the trunnions are rotatably mounted, gearing at one end of the drum for rotating the latter, and including a pair of gears movable at will into and out of driving engagement, the arm at the opposite end of the drum and said end of the drum being relatively movable whereby said end of the drum may be readily demounted to permit a substantially tubular garment to be slipped over the drum from one end and surround the same. 50

In testimony whereof, we hereunto affix our signatures.

WILLIAM G. YATES.
GEORGE C. FATSCHER.
